ATTORNEY.

UNITED STATES PATENT OFFICE.

BERNARD M. WELLS AND FREDERICK W. SIMISTER, OF PATERSON, NEW JERSEY.

HAMMER WITH SHINGLE-CUTTING ATTACHMENT.

No. 920,228.

Specification of Letters Patent.

Patented May 4, 1909.

Application filed April 22, 1908. Serial No. 428,625.

To all whom it may concern:

Be it known that we, BERNARD M. WELLS and FREDERICK W. SIMISTER, citizens of the United States, residing in Paterson, Passaic county, New Jersey, have invented a certain new and useful Improvement in Hammers with Shingle-Cutting Attachments; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide a knife attachment for hammers and similar implements which shall be simple and inexpensive in construction and capable of being readily and securely attached to various sizes and shapes of hammers; when the knife is attached to the hammer, it forms an implement which may be used interchangeably either as a hammer or as a means for trimming shingles and other similar purposes.

The invention will be found fully illustrated in the accompanying drawings, where-in,

Figure 1 is a side view of a hammer with the knife attachment in place thereon; Fig. 2 is a rear view of what is shown in Fig. 1; Fig. 3 is a perspective view of the attachment; and, Fig. 4 is a sectional view of the attachment and of a fragment of the hammer, on line x-x, Fig. 1.

In the drawings, *a* designates the head of a hammer, having the usual nail-driving portion *b* and the claw-portion *c*, and *d* is the handle of the hammer.

e designates the knife-attachment. This consists of a curved flat blade *f*, having its convex edge *g* sharp, and the laterally extending attaching members *h* and *i* preferably formed as integral parts of the blade.

The member *h* is a strap-shaped part extending downwardly from the forward end of the blade *f*, then bent laterally in a right angle, then bent upwardly in a right angle, and then bent laterally again in a right angle, and then bent downwardly in a right angle. There is thus formed a clamp *j* one side *k* of which is not only spaced from the other side *l* so as to receive the head of the hammer, but is also spaced or offset with relation to the blade *g*.

The member *i* is substantially a laterally extending strap shaped loop the opening *m* of

which is sufficiently large to receive one of the claws of the hammer. The loop is of such formation (see Figs. 2 and 3) as to bring the opening thereof in offset relation to 60 the blade *g*.

In the side *l* of the clamp *j* is arranged a set screw *n* which preferably has a sharp point *o* (see Fig. 4).

In assembling the knife attachment and 65 the hammer, the loop *i* is slipped over one of the claws of the hammer and the clamp made to receive the head of the hammer in the manner shown in Figs. 1 and 2, where-upon the set screw is manipulated to secure 70 the clamp to the hammer-head. If desired, the user may dent the side of the hammer-head, as with a nail-set, so that the point *o* of the screw may engage in such dent to afford a better grip for the screw on the 75 hammer-head.

The implement thus produced may be used either as a hammer for driving nails or, by means of its claws, for drawing them, or it may be used for trimming shingles and the 80 like by a chopping stroke; the offset relation of the blade with respect to the hammer-head affords clearance for the shavings produced.

Having thus fully described our invention, 85 what we claim as new and desire to secure by Letters Patent is:

1. The combination, with a hammer, of a cutting attachment therefor comprising a blade disposed substantially side by side 90 with the head of the hammer and means substantially at the ends of said blade for securing the attachment to the hammer, substantially as described.

2. The combination, with a hammer, of a 95 cutting attachment therefor comprising a blade disposed substantially side by side with the head of the hammer; and attaching means comprising a laterally projecting open clamp adapted to receive a part of the hammer, and a set-screw arranged in the clamp and adapted to bind against the hammer, substantially as described.

3. The combination, with a hammer, of a cutting attachment therefor comprising a 105 blade disposed substantially side by side with the head of the hammer and means, formed rigid with respect to the blade, for securing the attachment to the hammer, substantially as described.

4. As an article of manufacture, a cutting attachment for hammers and the like tools

consisting of a blade, and attaching means carried by the blade and comprising a loop-shaped member adapted to receive a part of the tool, an open clamp adapted also to receive a part of the tool and a screw in the clamp adapted to bind against the tool, substantially as described.

In testimony, that we claim the foregoing,

we have hereunto set our hands this 18th day of April, 1908.

BERNARD M. WELLS.
FREDERICK W. SIMISTER.
